(57) **CLAIM**

An ornamental design for an electric razor, as shown and described.

DESCRIPTION

FIG. 1 is a top perspective view showing my new design for an electric razor;

FIG. 2 is an elevational view thereof;

FIG. 3 is another elevational view thereof;

FIG. 4 is another elevational view thereof;

FIG. 5 is another elevational view thereof;

FIG. 6 is a top plan view thereof; and,

FIG. 7 is a bottom perspective view thereof.

The broken lines shown in FIG. 7 illustrate a portion of the electric razor and form no part of the claimed design.

1 Claim, 7 Drawing Sheets
